UNITED STATES PATENT OFFICE.

FRANCIS J. HICKEY, OF SACRAMENTO, CALIFORNIA, ASSIGNOR OF ONE-HALF TO JAMES M. DUNNIGAN, OF SACRAMENTO, CALIFORNIA.

STEAM-BOILER.

No. 823,864.

Specification of Letters Patent.

Patented June 19, 1906.

Application filed September 29, 1905. Serial No. 280,610.

To all whom it may concern:

Be it known that I, FRANCIS J. HICKEY, a citizen of the United States, residing at Sacramento, in the county of Sacramento and State of California, have invented new and useful Improvements in Steam-Boilers, of which the following is a specification.

My invention relates to improvements in steam-boilers, and is especially adapted for boilers of the locomotive type.

It consists of a cylindrical extension from the rear of the ordinary boiler with an inclosing shell and a fire-box of heat-resisting material and without water-legs.

It also comprises details of construction, which will be more fully explained by reference to the accompanying drawings, in which—

Figure 1 is a longitudinal vertical section of my construction. Fig. 2 is a transverse section taken through the fire-box.

In the ordinary construction of boilers the fire-box consists of double sheets of metal having a great number of connecting stay-bolts and forming what are known as "water-legs" extending down around the furnace portion of the boiler. The cylindrical boiler-shell connects with this fire-box portion and extends forward therefrom. In my invention I dispense with the ordinary form of fire-box, substituting therefor a shell lined with a heat-resisting material not adapted to form water-legs or contain water, and this furnace is made of any suitable or required length for the purpose for which it is to be used. To the rear of the ordinary boiler-shell is secured an annular head, and to this head is secured a cylindrical shell extending into the fire-box and having tubes within it continuous with those of the main boiler.

A is a boiler-shell of any usual or suitable construction. In the present case this shell is shown as cylindrical at the front, connecting with the front combustion-chamber B in the usual manner for locomotive-boilers. The portion A' of the boiler-shell is of somewhat larger diameter than the part A and is connected by the tapering section A². This is an ordinary construction for such boilers.

2 is an annular head having flanges 2^a and 2^b, the former flange being riveted inside of the rear end of the main boiler-shell and

the flange 2^b forming an open circle of 55 smaller diameter than the main shell. Into this flange 2^b is riveted a cylindrical shell 3, which forms the rear extension of the boiler and may be of any suitable length, depending upon the size of the furnace, which may be 60 as much as seven feet. The rear head 4 of this cylindrical shell is perforated to receive the flues 5, the front ends of which are secured in the front head 6 of the main boiler-shell. The flues thus have as much greater 65 length than that of the ordinary boiler-shell as will equal the length of this cylindrical extension, and this added length will greatly increase the heating-surface available for the production of steam.

7 is an outer shell of a size substantially equal to the diameter of the portion of the main boiler-shell A' and is riveted thereto, extending rearward some distance behind the cylindrical extension 3, and it has a head 75 8 with a door-opening, as at 9. This shell 7 is secured to the upper part of the extension 3 by sheet-metal segments 10 and by flanges, by which the segments are riveted to the shell and the extension.

The fire-box or furnace consists of shell 11, the rear portion of which forms an arc extending from the rear head 4 of the extension 3 and above the level of the flues 5, curving downward and extending to the bottom of 85 the space designed for the furnace. This and the exterior walls of the part 7 are, as shown, substantially vertical in the lower part. Within this shell 11 is fitted a heat-resisting compound, which may be made of 90 asbestos, fire-clay, pulverized fire-brick, cement, or other good heat-resisting compound. This compound forms a lining for the shell 11 and is held in place by brackets 12. These brackets or anchors may be 95 made in any suitable manner. I have shown them made of strips of sufficiently heavy metal having a flange turned upon one edge, by which they are riveted to the shell, and the other edge split at intervals with flanges 100 turned alternately toward opposite sides. These alternately-bent flanges extend into the material forming the lining and serve to hold it in place, thus forming a complete furnace-lining without any necessity of the 105 usual water-legs.

Any suitable form of fuel may be used, such as coal or oil, and if oil is used it will be

injected by a suitable burner into the space beneath the shell 3, thence returning beneath the shell toward the rear, the products of combustion entering the flues 5 and passing 5 to the front combustion-chamber B in the usual manner. That portion of the exterior shell 7 surrounding the upper part of the shell 3 and behind the furnace proper forms, with these parts, an air-space, which, inclosing 10 the shell, prevents any radiation and loss of heat therefrom. It will be seen that by this construction when the boiler and its flues begin to be heated the expansion of all parts will be symmetrical and in the same direction and will greatly reduce the danger of 15 leaky joints.

Having thus described my invention, what I claim, and desire to secure by Letters Patent, is—

- 20 1. A steam-boiler having in combination a main boiler-shell, a cylindrical rearward-extending shell of smaller diameter, an annular head connecting the two shells, an exterior shell having a diameter substantially equal 25 to the diameter of the rear end of the main shell, and secured thereto and extending over and beyond the smaller rearward-extending shell, flues extending through the main and supplemental shells, and a shell within the 30 fire-box and inclosing the lower rear portion of the supplemental shell, said fire-box shell having a lining of non-conducting material.
2. A steam-boiler having two diameters forming main and supplemental shells, an exterior shell having a diameter substantially equal to that of the main shell and greater than that of the supplemental shell, said exterior shell extending rearward over and beyond the supplemental shell, flues extending 35 through the main and supplemental shells, and a fire-box of non-conducting material within the exterior shell and inclosing the lower rear portion of the supplemental shell.
3. In a boiler, a main boiler-shell having a 40 rear head formed with flanges and a central opening, a cylindrical extension riveted into the inner flange of said head and having a head at its rear end, flues connecting said rear head of the extension and the front head 45 of the main boiler-shell, an exterior shell having the upper segmental portion riveted to the rear of the main boiler-shell and extend-

ing behind the extension of said shell to form an inclosure therefor, segmental plates riveted to the interior of said shell and to the top 55 of the extension, and a heat-resisting furnace located interior to the said shell.

4. In a boiler, a main shell, an extension rearward thereto of smaller diameter, an exterior shell having its front end secured to 60 the rear end of the main shell and extending rearward over and beyond the rear end of the supplemental shell, flues extending through the rear and front heads of the main and supplemental shells respectively, a furnace inclosed by the exterior shell, said furnace consisting of a shell inclosing and surrounding a lower portion of the boiler extension, said shell having a heat-resisting lining, and means for locking said lining to the shell. 70

5. In a boiler, a main shell, a supplemental shell of smaller diameter extending rearward therefrom, an exterior shell secured to the main shell and extending over and beyond the rear end of the supplemental shell, 75 flues connecting the rear and front heads of the main and supplemental shells, a furnace within the exterior shell and consisting of a metal shell inclosing the lower part of the boiler extension, a non-conducting lining for 80 said metal shell, and brackets riveted to the shell having oppositely-turned flanges projecting and interlocking with the lining substance.

6. In a boiler, a main shell, an extension 85 rearward of smaller diameter, flues connecting the rear head of the extension with the front head of the boiler, a furnace consisting of a metal shell inclosing the lower portion of the boiler extension and having a heat-resist- 90 ing lining as shown, an exterior shell extending from the rear of the main boiler-shell inclosing the upper part of the cylindrical extension and the exterior of the furnace, and brackets connecting said shell with the upper 95 part of the extension.

In testimony whereof I have hereunto set my hand in presence of two subscribing witnesses.
